E. L. YANCEY

United States Patent Office.

EDWIN L. YANCEY, OF BATAVIA, NEW YORK.

Letters Patent No. 97,847, dated December 14, 1869.

IMPROVEMENT IN HARVESTER-KNIFE GRINDER.

The Schedule referred to in these Letters Patent and making part of the same.

To all whom it may concern:

Be it known that I, EDWIN L. YANCEY, of Batavia, in the county of Genesee, and State of New York, have invented a certain new and improved Machine for Grinding Harvester-Cutters, &c.; and I do hereby declare that the following is a full and complete description of the construction and operation of the same, reference being had to the accompanying drawings, making part of this specification, in which—

Figure 1 is a side view of the machine.

Figure 2, an end view.

Figure 3, a view of the opposite side of fig. 1.

Like letters of reference refer to like parts in the different views.

The nature of this invention relates to a device used in connection with a grindstone, whereby the knives of a harvester are held in proper position to the stone for grinding, so that the cutting edge of the same shall be uniformly true and of the same level.

In fig. 1—

A represents a frame, on which is supported a stay or standard, B.

Said stay is secured to the frame by means of a finger-screw, C, passed through a slot in the rail of the frame, so that the stay can be adjusted to any place on the rail that may be desired.

D is the stone, and, as will be seen, is hung to the upper end of the standard on the shaft E, fig. 2.

Said stone is driven by the cog-wheel and pinion F G, journaled between the cheeks of the standard, as shown in fig. 2.

H are horizontal arms, secured one at each end of the top of the frame, to the extreme end of which are pivoted the standards of the frame I.

To the rail of said frame is secured the sickle or knives of the machine, by means of the hooks a, fig. 1, passed through the rail, and drawn upon the knives by the thumb-screws K, as shown in fig. 2.

The practical operation of this machine is as follows:

The knives, as will be seen, are held parallel with

the frame A, thereby bringing them in such relation to the stone that the edge of the section is brought against its side, and on which it is ground.

In order that the side of the stone shall conform to the special angle of the section, the stay or standard supporting the stone is adjusted in such direction as to bring the corner of the stone within the angle of the two sections, and the basil of the cutting-edge against it. In this position of the section to the stone, the angle of the basil is preserved alike in each section, and which may be more or less acute or obtuse, as the nature of the work may require.

The stone once set to the proper angle, one edge of each section is ground while in this position, the section being pressed against the stone by the springs P, or by a cord and weight, Q, arranged for that purpose.

One section being ground, another is brought to the stone by moving them along from one to another, until the whole have been ground.

The opposite edges are then ground, by changing the position of the stone so as to bring the opposite corner into the angle of two sections, the grinding of which then proceeds as before.

By the use of this apparatus, much labor is saved to those grinding the knives, as they are not required to hold them in their hands to the stone. The grinding is also better done, as all the knives are ground at the same angle, hence will be uniform in size, and will, therefore, cut cleaner and easier.

What I claim as my improvement, and desire to secure by Letters Patent, is—

A machine for grinding harvester-blades, consisting of a slotted frame, A, adjustable standard B, gearing F G, stone D, hinged frame I, and spring P, constructed, combined, and arranged to operate substantially as described, and for the purpose set forth.

EDWIN L. YANCEY.
